TO AUTOMATIC ELECTRIC COMPANY, OF CHICAGO, ILLINOIS, A CORPORATION OF
ILLINOIS.

TELEPHONE DISTRICT EXCHANGE SYSTEM.

1,306,825.

Specification of Letters Patent. Patented June 17, 1919.

Application filed August 11, 1913, Serial No. 784,111. Renewed August 3, 1918. Serial No. 248,222.

To all whom it may concern:

Be it known that we, BERNARD D. WILLIS, and TALBOT G. MARTIN, both citizens of the United States of America, and residents of 5 Chicago, Cook county, Illinois, have invented certain new and useful Improvements in Telephone District Exchange Systems, of which the following is a specification.

Our invention relates to a telephone exchange system which is divided into a certain number of districts or main offices, and sub-divided into a number of branch offices which have access to a certain number of the main offices. In such a system the main office 10 of each district is connected by trunk lines with the main office of each of the other districts, while the branch offices of each district are connected by trunk lines with the main office of their own district only. Calls from 15 one main office to another main office pass direct from the main office in which the call originates to the main office in which the called subscriber is located. Any call to or from a branch office must pass through the 20 main office to which that branch office belongs.

In systems of this character it has heretofore been necessary when one subscriber of a branch office called another subscriber of 30 the same office that the connection first had to be trunked from the branch office to the main office and then back from the main office to the branch office. Thus, although both the lines of the calling and the called 35 subscribers terminated in the same branch office, two trunk lines between the main and branch offices were included in the connection between the two lines.

It is an object of our present invention to 40 provide means whereby connections between two subscribers of the same branch office may be confined entirely to local apparatus in the branch office and thereby avoid the use in such connections of any trunk lines 45 extending between the main and branch offices.

It is a special object of our invention to accomplish this without in any way disturbing the general trunking scheme, or requiring 50 the subscribers of a branch office to call any special numbers or perform any other acts other than to call the regular directory number of the subscriber desired.

A further special object of our invention 55 is the provision of a repeater at a branch office which operates to repeat impulses cor-

responding to the various digits of the called number to switches located at the same branch office or main office until it is definitely determined that the call is to extend 60 to another subscriber of the same branch office. This repeater then operates to cut off and release all switches which have been previously operated, and to extend the connection directly to other switches in the same 65 branch office, through which last-mentioned switches the call is then completed to the desired line.

In order that our invention may be more clearly understood, we have illustrated in 70 the accompanying drawings an automatic district telephone system in which automatic switches of various well-known types are employed in combination with the novel features of our invention. It is, of course, 75 understood that if desired our invention can be employed with switches of other types without departing from the spirit of our invention.

In the accompanying drawings— 80

Figure 1 represents diagrammatically the lay-out of a multi-office telephone system embodying the principles of the invention disclosed herein.

Fig. 2 is a diagram showing more in detail 85 the trunking arrangement of a portion of the system shown in Fig. 1.

Figs. 3, 4, 5 and 6 show a complete connection between a calling telephone T' and a called telephone T² in the system shown. 90

Fig. 7 shows the circuit of an additional apparatus which is employed in the system.

Figs. 8, 9 and 10 are diagrams representing the connections of the contacts of the selector-repeater L' to meet various requirements. 95

Fig. 11 represents a selective signaling ring-back device for use in connection with party lines.

As shown in Fig. 1, the system represented 100 herein is a multi-office or district system comprising a plurality of exchange offices A, B, C, D, A', A², B', B², etc. With respect to the trunk connections between offices, these offices are divided into two classes. 105 The offices A, B, C and D are each connected with each of the others by a separate set of trunk lines, and for convenience these offices will be designated as main offices. The offices A', A², B', B², etc., are each connected by trunk lines to only the nearest main office A, B, C or D, as the case may be. These 110

offices A' , A^2 , B' , B^2 , etc., will be termed branch offices. In a system of this character, when a subscriber whose line terminates at one of the main offices (office A , for example) wishes to communicate with a subscriber whose line terminates at one of the other main offices (office C , for example), the calling subscriber's line is connected through the medium of suitable apparatus at his own office (office A) to a trunk line leading directly to the office of the called subscriber (office C), at which office said trunk line is connected through the medium of suitable apparatus with the line of the called subscriber. If a subscriber of one of the branch offices (office A' , for example) wishes to call a subscriber of some other office, he must first obtain connection with a trunk line leading to his main office (office A). At this office connection may then be made with a trunk line leading to the office of the called subscriber, providing the called subscriber's line terminates in one of the main offices, or in another branch office (such as office A^2) which is connected to the same main office as the calling subscriber. If the called subscriber's line terminates at a branch office (office C' , for example) of a second main office (office C), the calling subscriber, after having obtained connection over a trunk line with apparatus in his own main office (office A), must then obtain connection with a trunk line leading to said second main office (office C), and then, through the medium of apparatus at said second office, be connected with a trunk line leading to the branch office (office C') of the called subscriber, where the connection is finally completed. Following out this general plan, if a subscriber of a branch office desired to obtain connection with a second subscriber of the same branch office, it was heretofore necessary that he first obtain connection with a trunk line leading to a main office to which his branch office is connected, and would then obtain connection with a second trunk line leading back from the main office to the branch office, from which second trunk line connection would finally be completed to the called subscriber. It is the object of our present invention, however, to provide means whereby the trunk lines leading from the branch office to the main office and back from the main office to the branch office may be excluded from connections between the subscribers of the same branch office.

Referring to Fig. 2, the method of carrying out the invention is, in general, as follows: The apparatus inclosed within the dotted lines represents the apparatus of a branch office, while the remaining apparatus is assumed to be located at a main office. There are shown in this figure two groups of subscribers' substations T^3 and T^4 the

line conductors of each of which terminate in an individual trunk-selecting or pre-selector switch E at the branch office. For the purpose of being called these lines terminate in the banks of a plurality of connector switches F . These connector switches are represented herein by small circles, three parallel lines underneath the same representing the multiple bank contacts which are assumed to be arranged in horizontal rows or levels. The individual switches E of each of the groups of subscribers' substations T^3 and T^4 have access to a group of trunk lines t which lead to so-called secondary trunk-selecting switches H . The switches H have access to trunk lines t' which lead to first selectors I in the main office. Associated with the main office there are shown three groups of subscribers' substations T^5 , T^6 and T^7 , each of which groups is provided at the central office with a group of preselecting or line switches E for calling purposes, and with connections in the banks of a group of connector switches F for being called. Each of the groups of line switches E have access to a group of first selector switches I , which first selectors in turn have access to second selectors J , which second selectors in turn have access to third selectors K . Although the bank contacts of all the first selectors shown in Fig. 1 are represented as being multiplied together, it is to be understood that this figure is only diagrammatic, and any known or desired multiplying arrangement of the selectors may be employed. As shown herein, the first level of the first selectors has access over trunk lines t^2 to second selectors J in the same exchange. The remaining two levels shown are assumed to have access to groups of trunk lines t^3 and t^4 leading to other main offices, where said trunk lines would terminate in second selectors. In like manner, the main office shown would be provided with groups of second selectors which are accessible to the first selectors of the other main offices in the system. The first level of the group of second selectors J has access to a group of third selectors K , the first two levels of which have access to trunk lines leading to connector switches F which have access to the subscribers' groups T^3 and T^4 in the branch office, while the remaining level (or levels) of the same group of third selectors has access to connectors belonging to the subscribers' group T^5 in the main office. The remaining groups of third selectors may have access to connectors all of which are situated in the main office, or some of which are situated in a branch office and some in the main office, or in any manner desired. In each of the trunk lines t which lead from the subscribers' individual switches E to the secondary switches H there is a switching device L which, under certain

conditions, may operate to connect the trunk line which has been seized by a subscriber's individual switch to a secondary switch M , which secondary switch has access to a connector in one or the other of the groups of connectors which have access to the branch office subscriber groups T^3 and T^4 . The secondary switches M are arranged to have individual terminals in the banks of the 5 switching devices L so that a switching device L always uses the same secondary in extending a connection to a line in a particular group. If a call is directed to a line in another group another secondary switch 10 M may be used which is also individual to the same device L .

In general the operation of the system shown in Fig. 2 is as follows: Upon the removal of the receiver by the subscriber of 15 one of the branch office groups, his individual line switch E operates to select a trunk line leading to a secondary switch H , which in turn operates to select an idle first selector I . The subscriber operates his calling device to cause the selected first selector to extend connection to an idle second selector in the section or division of the exchange to which the called subscriber belongs. The selected second selector is then 20 operated to extend connection to a third selector which has access to the next smallest subdivision of the exchange to which the called subscriber belongs. This third selector is then operated to establish connection 25 with an idle connector switch which has access to the group of subscribers to which the called subscriber belongs, which connector is then operated to establish connection with the called subscriber. Assume now 30 that the called subscriber is in the same branch office as the calling subscriber. Under these conditions, when the calling subscriber operates his calling device to cause the third selector to establish connection 35 with a connector switch, the switching apparatus L in the trunk line which has been seized by the calling subscriber's line switch operates to extend the connection directly through one of the secondary switches M 40 and over a trunk line t^6 directly to one of the connectors having access to the groups of subscribers T^3 or T^4 , depending upon the group in which the called subscriber is situated. In other words, when the trunking 45 has progressed to the stage of eliminating all the sections except the section to which the call is to revert, then the switching apparatus L is in order to cut off the balance of the system by switching to the local apparatus M . When the apparatus L thus operates to extend a connection by way of one 50 of the secondary switches M , it causes the secondary switch H which was previously selected, as well as all the selectors which 55 have been operated in the main office, to be 60 65

released and the connection is thereafter confined solely to the branch office.

The apparatus with which we have chosen to illustrate our invention is of a well-known type and is shown in patents of the 70 prior art, and it is therefore thought necessary to show only such details of construction as are necessary to bring out the novel features.

The telephone substation T' (Fig. 3) comprises the usual transmitter 2, receiver 3, switch hook 4, ringer 5 and condenser 6. Being an automatic substation it is also provided with a suitable calling device or impulse transmitter which is represented herein by a pair of impulse springs 7 and 8 and a toothed impulse wheel 9, which latter may be operated by the calling subscriber through the medium of a finger hole dial (not shown) to cause the impulse springs to 80 be opened a number of times corresponding to any digit which it is desired to call.

The subscriber's individual switch E' (Fig. 3), which may represent any one of the switches E shown in Fig. 2, is of the 90 general type of switches disclosed, for example, in British Patent to R. W. James No. 26,301 of 1906, being of the more particular form shown in British Patent to A. E. Keith No. 1421 of 1910. This line switch, 95 as is well known, is provided with a movable plunger which, when idle, is always maintained opposite the bank terminal of an idle trunk line by a so-called master switch, and upon the operation of said line switch this 100 plunger is forced into the terminal springs of said trunk line to connect the subscriber's line therewith. The master switch N which is shown herein differs somewhat from that 105 shown in said British Patent No. 1421 of 1910. The usual plunger guide shaft 9 is connected with a rotary shaft 10 in such a manner that as the shaft 10 is rotated back and forth the plunger shaft 9 is caused to 110 oscillate about said shaft 10 as an axis. The power for rotating the shaft 10 in one direction is furnished by a spring 11, while the power for rotating it in the other direction and for restoring tension to the spring 11 is furnished by a solenoid 12. Secured to the 115 shaft 10 there is a cam member 13 which is provided along its outer edge with a plurality of notches 14, one for each trunk line to which the line switches have access. The shaft 10 is normally locked against rotation 120 in either direction by the engagement of the lever 15 with one of the notches 14. A small governor 17 is provided for controlling the speed of operation of the master switch. The master switch is also provided with the 125 usual bank of contacts comprising a common segment 24 and an individual contact a for each trunk line. The usual wiper 25 serves to keep the common segment 24 in electrical contact with the individual con- 130

tacts of the trunk line before which the plungers of the idle line switches are resting.

Allotted to the calling subscriber's line there is also a call register or meter 26 which is operated by a double-wound magnet 27, which magnet is so wound and adjusted that it requires the energization of both windings in the same direction to cause the meter to be operated.

- 10 The apparatus shown at L' is one of the switching devices shown at L in the diagrammatic Fig. 2. This device performs two functions. In a call from the branch office to the main office it operates as an ordinary repeater to repeat the impulses from the calling substation around the condensers 28 and 29 to the branch conductors 30 and 31. In a local connection this device operates to free the trunk line leading to the 15 main office and to divert the call to the proper local switches for completing the desired connection. This switching repeater comprises a vertically and rotatably movable switch shaft (not shown) which carries the 20 wipers 35, 36, 37, 38 and 39 and is controlled by the so-called vertical and rotary magnets 40 and 41 in the manner shown in United States Letters Patent No. 815,176, granted March 13, 1906, to Keith, Erickson and 25 Erickson, for connector switches. There is a single row or level of bank contacts for each wiper and the shaft is preferably arranged to be capable of making twenty rotary steps. The switch shaft may be operated 30 in response to the first three digits of the called number, the impulses for the first digit operating to raise the shaft vertically and the impulses for the second and third digits operating to rotate it. The rows of 35 contacts are placed so as to be engaged by their respective wipers only when the switch shaft has been raised a number of steps corresponding to the first digit of the subscriber's numbers in the branch office. For 40 example, if the numbers in the branch office begin with the digit 1, whenever the dial is operated for the first digit 1 the wipers will be raised to a level of contacts, and if the first digit called by the first operation of the 45 dial is greater than 1, the wipers will obviously be raised above the levels of contacts, making it impossible for a reverting call to result with any number the first digit of which is any higher than 1 in unit value. In 50 the row of contacts which are engaged by the wiper 38 one contact is connected to ground through one winding of a double-wound relay 43. The position of this contact is determined by the units value of the second 55 digit of the subscribers' numbers in the branch office. For example, when the second digit of the subscribers' numbers in the branch office is 1, the connection to ground through the relay 43 will be from the first 60 contact (Fig. 8); but if the second digit 65 was 2 the connection would be made to the second contact instead of to the first, etc. In the rows of contacts which are engaged by the wipers 35, 36 and 37, certain of the contacts are connected by means of trunk 70 conductors, such as 240, 241 and 242, to secondary switches, such as the switch M' (Fig. 7), which corresponds to one of the switches M (Fig. 2). The contacts which are thus connected, as will be shown, do not coincide 75 with the position of the contact which is connected to ground through the relay 43, but are always displaced to the right (Fig. 8). The amount of this displacement varies, however. For example, if the third digit of 80 any subscribers' numbers in the branch office is 1, the contacts which are displaced only one step will be connected to a secondary switch; if the third digit of any of the branch office numbers is 2, the contacts which 85 are displaced two steps will be connected, etc. In other words, the contacts which are connected to the secondary switches M' are the ones which are engaged by said wipers 35, 36 and 37 when the switch shaft has been 90 rotated a number of steps equal to the sum of the second and third digits of the subscribers' numbers in the branch office. The contacts in the row which is engaged by the wiper 39, to which wires are connected, 95 coincide in position with the similar ones in the levels of wipers 35, 36 and 37. Furthermore, these wires are all multiplied (Fig. 8) and are connected to one of a normally open pair of contact springs 171 of the relay 43. 100 Since it is assumed that the repeater L' is adapted to be used in a branch office in which all subscribers' numbers begin with either 1-1-1 or 1-1-2, the rows of contacts are placed so that the wipers reach a position 105 opposite them on the first vertical step of the shaft. The first contact in the row which is engaged by the wiper 38 is connected to the relay 43, and in the rows which are engaged by the wipers 35, 36 and 37 the second 110 and third sets of contacts are connected to the switches M'. Since in this instance it is assumed that the number of the subscriber who is actually being called at the branch is 11220, in the drawings the third set and 115 this set of contacts only are actually connected, while stub conductors indicate similar connections from the second set of contacts, which would be used if 111XX were being called. With this arrangement it is 120 evident that when a subscriber of a branch office is calling another subscriber of the same office, when the second digit is called the wiper 38 will be brought into engagement with a contact which is connected with 125 the winding of the relay 43, viz., the first contact, and when the third digit is called this wiper, together with the others, will be carried on past the first position and the wipers 35, 36 and 37 will be brought into en- 130

gagement with a set of contacts (the set in third position) which are connected to a trunk line leading to the secondary switch M'.

- 5 The switching repeater L' is also provided with a so-called side switch similar to that shown in said connector Patent No. 815,176, which, however, comprises but a single wiper 44 and is controlled by an escapement magnet 45 in the usual manner. The magnet 46 is the usual release magnet for restoring the switch shaft and side switch to normal position upon the release of the connection. The operation of the selector-repeater is 10 controlled through the medium of a double-wound line relay 33, which is connected with the line conductors through the springs of a reversing relay 34. The relay 34 is double-wound and is so adjusted that it is operatively energized only when both windings are energized in the same direction. The talking circuit through the repeater, before reaching the condensers 28 and 29, passes through normally closed contacts of a 15 switching relay 47, to the normally open springs of which are connected the wipers 35 and 36. The relays 48 and 49 are slow acting—that is, relays that deenergize slowly after their energizing circuits have been 20 broken.

The secondary switches H' (Fig. 4) and M' (Fig. 7), which correspond respectively to one of the switches H and M (Fig. 2), are the same in principle as the subscriber's individual switch E', being somewhat simplified, however, in that they are provided with no line or cut-off relay armatures. Each of these switches belongs to a group which is controlled by a master switch similar to the master switch H (Fig. 3), there being shown, however, only the master switch N' which controls the switch H'.

- The selector switches I', J' and K', which may represent any one of the respective 45 switches I, J or K (Fig. 2), are of the general type of selector switches disclosed in United States Letters Patent No. 815,321, granted March 13, 1906, to Keith, Erickson and Erickson, being somewhat modified, 50 however, as shown in British Patent No. 1421 of 1910, hereinabove referred to, so as to operate in a two-wire system. Referring to the selector I', each of these switches comprises a bank of contacts arranged in 55 rows or levels and adapted to be engaged by a set of wipers 51, 52 and 53 which are carried by a vertically and rotatably movable shaft (not shown) which is controlled by the usual vertical and rotary magnets 54 and 55. 60 The usual side switch comprising the wipers 56, 57, 58 and 59 is controlled by the private magnet 60 in the usual and well-known manner. The usual release magnet 61 is adapted to release the switch shaft immediately upon energization, rather than by the

deenergization thereof as shown in said selector patent. The relays 62 and 63 are slow acting.

The connector switch F' Fig. 6, which may correspond to any of the switches F (Fig. 2), is of the general type of connectors shown in said United States Letters Patent No. 815,176, previously referred to, being modified, however, in order to operate in a two-wire system. In this figure, 64, 65 and 70 66 are the usual shaft wipers, which are carried upon the vertically and rotatably movable shaft which is controlled by the vertical and rotary magnets 67 and 68. The usual side switch is controlled by the private 75 magnet 69 in the well-known manner. At 70 there is shown the usual release magnet and at 71 the ringing relay is represented.

The telephone substation T² and individual switch E² are in all respects the same 80 as the telephone substation T' and switch E' (Fig. 3).

At O (Fig. 6) there is represented a ringing current generator. At Q and Q' (Figs. 3 and 6) there are represented two busy signaling machines. There are shown throughout the drawings a plurality of batteries X for supplying current for operating the central office apparatus and for talking purposes. There need, however, be but one battery, or, preferably, one battery in each 90 exchange.

Having given a general description of the system and apparatus in connection with which it has been chosen to illustrate the 100 invention disclosed herein, there will now be given a more or less detailed description of the operations by which the connections are established between the various subscribers. Since the apparatus shown herein is in general well known in the art and is fully described in the publications herein referred to, it is not thought necessary to describe 105 its operation in detail herein. It will first be explained how a connection is extended 110 from the telephone substation T' of a branch office to a telephone substation T² of another branch office, or of some main office. The number of the calling substation will be assumed to be 11110 and the number of 115 the called substation will be assumed to be 22220.

Upon the removal of the receiver at the calling substation a bridge is closed across the calling line through the transmitter 2 and receiver 3 by the closure of the hook switch contact 73, whereby an energizing circuit is closed through the line winding 74 of the subscriber's switch E'. The winding 74, upon energizing, attracts the armature 120 75, whereby a circuit is closed through the pull-in winding 76, which operates to attract the plunger arm 77 and cut-off armature 278. The plunger arm 77, upon being attracted, thrusts the plunger into its bank 125 130

of contacts, whereby the line circuit is extended through the springs 78 and 79 and 80 and 81 to the selector-repeater L', while the armature 278 operates to disconnect the 5 winding 74 from the line. When connection is extended to the repeater L' a circuit is closed through its line relay 33, said circuit extending from ground G' through the lower winding of said relay, springs 82 and 83 10 of the relay 34, back contacts of the spring 84 of the relay 47, line switch bank springs 81 and 80, line 85 of the telephone T', line 86, left-hand winding of the meter magnet 27, bank springs 78 and 79, back contact 15 of the spring 87 of the relay 47 and springs 88 and 89 of the relay 34 and upper winding of the relay 33 to the battery lead 90, and thence through the battery X to ground G. The relay 33, upon energizing, closes a 20 circuit from ground G² through the front contact of the spring 91 and relay 48 to the battery lead 90. One result of the energization of the relay 48 is the closure of a circuit extending from ground G² through the 25 springs 92, 93 and 94 and line switch bank springs 95 and 96 and winding 97 of the line switch E' to the battery lead 90. The winding 97, upon energizing, serves to hold the switch E' in its operated position after the 30 line winding has been disconnected from the line and permitted the circuit of the winding 76 to be broken. A further result of the energization of the relay 48 of the repeater L' is the closure of a circuit from ground G² through the springs 35 92 and 93 and the lower winding of the relay 34 to the battery lead 90. A third result of the energization of the relay 48 is the closure of a circuit extending from ground G² through the springs 40 92 and 93, contact 98 of the relay 47, and thence over the trunk conductor 32 and through the winding 99 of the switch H' (Fig. 4) and springs 100 and 102 and contact 103 in the master switch N' to the battery lead 90. The switch H' thereupon operates to extend the connection through the contacts 104 and 105 to the first selector I', while at the same time, by the shifting of the springs 100, 101 and 102, the winding 99 45 50 is connected to the battery lead through the high resistance winding 107, so as to reduce the holding current of the switch H'. A further result of the energization of the line relay 33 of the selector-repeater L' when connection is first extended thereto is the closure of a bridge across the trunk conductors 30 and 31, whereby, as soon as connection is extended to the first selector I', as above described, an energizing circuit is 55 closed for its line relay 109. This circuit extends from ground G⁴ at the selector through the lower winding of said relay 109, side switch wiper 59, trunk conductor 110, contact 105, conductor 31, contact 111 of the 60 65 repeater line relay, upper winding of the 70 75 80 85 90 95 100 105 110 115 120 125 130 relays 112 and 34 in series, conductor 30, contact 104, side switch wiper 56 and the upper winding of the selector line relay 109 to the battery lead 115. The relay 109, upon energizing, closes the circuit of the slow acting release relay 116. At the selector-repeater L' the current flowing through the upper winding of the relay 34 in the circuit last traced is opposed by the current in the lower winding, and said relay is not operatively energized. The current flowing in the upper winding of the relay 112, however, causes said relay to be operated to open the contact 117 to prevent the application of busy signaling current to the calling line in a manner which will be explained herein-after. It will be remembered that when connection was first extended to the repeater L' its line relay was included in an energizing circuit which included the left-hand winding of the subscriber's meter magnet 27. The current in this latter winding, however, is opposed at this time by current flowing in the right-hand winding over a circuit extending from ground G² at the relay 48 in the repeater L' to the line switch bank springs 95 and 96, as has previously been traced, thence through the right-hand winding of the magnet 27 and contact 121 to the battery lead 90. The magnet 27 is therefore not operatively energized at this time. The closure of the contact 122 by the operation of the subscriber's switch E' completes a circuit extending from ground G² through said contact, master switch bank contact 123, wiper 25 (which is assumed to be resting upon said contact at the time), segment 24 and the relay 124 to the battery lead 90. The relay 124, upon energizing, closes the circuit of the relay 16, which withdraws the locking member 15 from the cam 13 and permits the idle plungers to be moved away from the trunk line seized by the switch E'. When the wiper 25 engages the non-grounded contact of the first idle trunk line, the relays 124 and 16 deenergize and the locking member 15 is permitted to drop back into the cam 13 and bring the plungers to rest in front of said idle trunk line. When the plungers in their search for an idle trunk line pass beyond the last trunk, the arm 22 closes the contact 23, whereby the circuit of the relay 18 is closed, said circuit extending from ground G⁷ through the springs of the relay 124 (which is energized at the time), contact 23, relay 18 and the contact 125 of the relay 16 (which is also energized at the time) to the battery lead 90. The relay 18, upon energizing, becomes locked in its operated position by the engagement of the spring 19 with the detent on the spring 20, and closes an energizing circuit for the solenoid 12 and a locking circuit for the relay 124 independent of the master switch bank. The solenoid, upon energizing, ro-

- tates the plungers back past all the trunk lines to their starting positions, whereupon the arm 21 releases the spring 19 from the spring 20 and the plungers again come under 5 the control of the master switch bank and come to rest upon the first idle trunk line. Upon the closure of the contact 106 (Fig. 4), the master switch N' operates in the same manner as explained for the master switch 10 N to select an idle trunk line for the idle switches of the group to which the switch H' belongs.

The foregoing operation takes place immediately upon the removal of the receiver 15 from the switch hook at the calling substation. The calling subscriber now operates his calling device in the usual manner for the first digit 2 of the called number, whereby the substation impulse springs 7 and 20 8 are separated twice momentarily. Each time the substation impulse springs are separated, the line relay 33 of the repeater L' is momentarily deenergized. The breaking of the contact 111 each time the relay 33 de- 25 energizes opens the bridge across the trunk conductors 30 and 31, thereby momentarily breaking the energizing circuit of the line relay 109 of the first selector I'. The relay 48 in the repeater being slow acting does not 30 deenergize during the momentary interruption of its circuit by the line relay 33, and therefore each time the spring 91 engages its back contact, an impulse is transmitted over the circuit extending from ground G² 35 through the back contact of the spring 91, contact 126 of the relay 48, vertical magnet 40 and side switch wiper 44 in multiple with the relay 49 to the battery lead 90. The vertical magnet 40 receives two impulses over 40 this circuit and operates to raise the switch shaft two steps. This operation of the switch shaft results in raising the wipers above the level of the bank contacts, as it has been assumed that the calling subscriber is not 45 calling another subscriber in his own branch office. The slow acting relay 49 is energized by the first impulse transmitted through it and remains in its operated position until after the last impulse is delivered for the 50 digit. In its operated position the relay 49, by shifting the spring 127 out of engagement with its back contact and into engagement with its front contact, opens one side of the talking circuit through the repeater and 55 short-circuits the upper winding of the relays 112 and 34, so as to remove their resistance from the circuit of the line relay of the selector I' while impulses are being transmitted through it. The closure of the contact 129 by the relay 49 completes an energizing circuit for the escapement magnet 45. Upon the breaking of this latter circuit, when the relay 49 deenergizes after the last impulse for the digit is delivered 60 65 from the substation, the escapement mag-

net 45 deenergizes and permits the side switch wiper 44 to pass from first to second position. The two impulses which are transmitted to the line relay 109 of the first selector I' by the relay 33 of the repeater L' cause two impulses to be transmitted through the vertical magnet 54 of the selector in series with the slow acting private magnet relay 63, whereby the wipers of the said switch are lifted two steps. The private 70 magnet relay 63, in its energized position, closes the circuit of the private magnet 60, which, after the last impulse for the digit is transmitted, deenergizes and permits the side switch to pass to second position. The 75 rotary magnet 55 thereupon begins to operate in a well-known manner and rotates the wipers 51, 52 and 53 onto the contacts of a trunk line leading to an idle second selector J', after which the side switch passes to 80 third position and through the medium of its wipers 56 and 59 completes the connection between the calling line and said second selector over the heavy conductors shown in the drawings. 85

The substation calling device is now operated for the second digit 2, whereby the repeater L' is caused to operate in the same manner as for the previous digit to repeat two impulses to the second selector J', which 90 latter operates in the same manner as explained for the first selector I' to extend connection to an idle third selector K'. Since the side switch wiper 44 of the repeater L' is in second position when the second digit is 95 called, its rotary magnet 41, instead of the vertical magnet 40, is operated, which operation merely rotates the shaft of the repeater without carrying the wipers onto any circuits. The escapement magnet 45 is operated in the same manner as for the previous digit and causes the side switch wiper 44 to pass to third position after the last impulse is delivered. In third position the side switch wiper 44 connects the switching relay 47 100 with the battery lead 90. This, however, does not affect the relay 47, since its other terminal is connected to the wiper 39 and therefore terminates in an open circuit, the wiper 39 being now in the second level and 105 out of engagement with its bank contact. When the substation calling device is operated for the third digit 2, the repeater L' operates to repeat the two impulses to the third selector K', which operates in the same manner as the previous selectors to extend the connection over the conductors 133 and 134 110 to an idle connector F', whereupon the line relay 136 of said connector becomes energized and closes a circuit through the slow 115 acting release relay 137. When the substation calling device is operated for the fourth digit 2, the repeater line relay 33 operates to 120 momentarily interrupt the circuit of the connector line relay 136 twice, whereby two 125 130

impulses are transmitted through the vertical magnet 67 in series with the slow acting private magnet relay 138. The vertical magnet operates in response to these impulses to raise the switch shaft two steps, while the relay 138 operates in the usual manner to cause the private magnet 69 to release the side switch from first to second position after the last impulse for the digit 10 is delivered to the vertical magnet. Upon the operation of the substation calling device for the last digit 0, ten impulses are repeated by the repeater relay 33 to the connector line relay 136. Since the side switch 15 of the connector is now in second position, the operation of the connector line relay 136 for this digit causes ten impulses to be transmitted through the rotary magnet 68 and relay 138. The rotary magnet 68 operates in response to these impulses to rotate the wipers 64, 65 and 66 onto the contacts of the called line, after which, if said line is idle, the side switch passes to third position. If the called line is busy, the side switch is 20 locked in second position and the calling subscriber is given a busy signal from the busy signaling device Q' in the well-known manner. It will be assumed that the called line is idle and that the side switch passes to 25 third position. The engagement of the side switch wiper 140 with its third-position contact point extends a guarding potential from ground G^s through said side switch wiper and shaft wiper 66 to the connector private 30 bank contacts of the called line and completes an energizing circuit for the cut-off winding 141 of the called subscriber's individual switch E². The winding 141, upon energizing, is not strong enough to attract 35 the plunger arm 142 from its normal position, but attracts the cut-off armature 143, whereby the switch is disconnected from the line and the contact 144 in the talking circuit is closed. The side switch wiper 145, 40 upon passing to third position, completes a circuit for the ringing relay 71, which circuit extends from ground G^s through the interrupter 146, relay 71, back contact of the spring 147 of the relay 148 and through the 45 side switch wiper 145 to the battery lead 115. The relay 71, upon energizing, disconnects the calling line from the called line and connects the ringing current generator O with the latter to signal the called subscriber. 50 Since the circuit of the relay 71 includes the interrupter 146, said relay is energized only intermittently so as not to ring the called subscriber continuously. When the called subscriber removes his receiver from the 55 switch hook, or as soon thereafter as the relay 71 de-energizes, if it is energized at the time, the called substation is provided with talking current which flows over a circuit extending from ground G^s at the connector 60 switch through the said switch wiper 140, 65

the lower winding of the back-bridge relay 149, ringing relay springs 150, side switch wiper 151, shaft wiper 65, thence over the line circuit to and through the substation T², back over the other side of the line, through 70 the contact 144 at the switch E², connector wiper 64, ringing relay springs 153, contact 254, upper winding of the relay 149 and side switch wiper 145 to the battery lead 115. The relay 149, upon energizing, closes a circuit 75 extending from ground G^s through the side switch wiper 140, reversing relay 148 and the contact 154 to the battery lead 115. The relay 148, upon energizing, by shifting the spring 147 out of engagement with its 80 back contact and into engagement with its front contact, interrupts the circuit of the ringing relay 71 and forms a locking circuit for itself. The shifting of the springs 155 and 156 out of engagement with their back 85 contacts and into engagement with their front contacts transposes the connections between the windings of the line relay 136 and the trunk conductors 133 and 134, whereby the direction of current flowing in said conductors and in the bridge comprising the upper windings of the relays 34 and 112 at the repeater L' is reversed. The reversal of current in the upper winding of the relay 34 causes said relay to assist the lower winding 90 of the same and said relay is operatively energized. The relay 34, upon operating, reverses the current in the calling line, whereby the left-hand winding of the subscriber's meter magnet 27 is caused to assist the right-hand winding and said magnet is operatively energized to advance the meter 26 one step to register the call. Upon the energization of the magnet 27, the contact 157 is 95 closed, whereby the left-hand winding of 100 said magnet is short-circuited and the magnet is thereafter maintained in its operated position by the right-hand winding alone. 105

Upon the completion of the conversation the entire connection is automatically released by the hanging up of the receiver at the calling substation. When said receiver is hung up, the circuit of the repeater line relay 33 is permanently broken. The opening of the contact 111 by the de-energization 110 of the relay 33 at this time permanently breaks the circuit of the connector line relay 136. The relay 136, upon de-energizing, 115 breaks the circuit of the release relay 137, as well as the holding circuits of the release relays 160, 161 and 116 of the selectors K', J' and I', the circuits of which relays are maintained closed solely by the connector line relay 136 after the side switch wiper 162 passes to third position. The relays 137, 160, 161 120 and 116, upon de-energizing, close the circuits of their respective release magnets 70, 163, 164 and 61, which, upon energizing, immediately restore their switch shafts and side switches to normal position and the cir- 125 130

cuits of the release magnets are finally broken at the off-normal contacts when the switch shafts reach their lowest positions. At the repeater L' a further result of the de-
5 energization of the line relay 33 is the breaking of the circuit of the relay 48, which, upon deenergizing, breaks the circuit of the relay 118, holding winding of the switch E' and windings 99 and 107 of the switch H'
10 (Fig. 4). The relay 118, upon deenergizing, closes the circuit of the release magnet 46, which circuit extends from ground G¹⁰ through the back contact of the spring 166, off-normal contact 167 and release magnet
15 46 to the battery lead 90. The magnet 46, upon energizing, restores the shaft and side switch of the repeater to normal position, and when the shaft reaches its lowest position it opens the circuit of the magnet 46 at
20 the contact 167. The breaking of the holding circuits of the switches E' and H' permits said switches to be restored to normal position and all the apparatus employed in the connection is left in readiness for another call.
25

It will now be explained how a subscriber of the branch office may obtain connection with another subscriber of his own branch office without monopolizing the trunks leading to the main office. For instance, it will be assumed that the subscriber at the substation T' (whose number is 11110) desires to call subscriber No. 11220, who, it will be assumed, is connected to the same branch office. Upon the removal of the receiver at the calling substation, the switch E', the repeater L' and the switch H' operate in the same manner as heretofore described to connect the calling line with an idle first selector I' in the main office. The calling subscriber now operates his calling device for the first digit 1, whereby the first selector in the main office is operated to extend connection to an idle second selector connected to
30 its first level in the usual manner, and the wipers of the repeater L' are raised one step, which, in the case assumed, brings said wipers to a position opposite their respective rows or levels of contacts. The side switch
35 wiper 44 of the repeater L' passes to second position in the usual manner after this first digit is called. The calling subscriber now operates his calling device for the second digit 1, whereby the second selector which
40 has been selected in the main office is operated in the usual manner to select an idle trunk line connected to its first level. At the repeater L' the impulse for this second digit causes the shaft of said repeater to be
45 rotated a single step, whereupon the wiper 38 engages the contact 168, which is connected to the upper winding of the relay 43. A circuit is thereupon completed from ground G¹¹ through the upper winding of
50 said relay, contact 168, wiper 38 and the es-

capement magnet 45. The closure of this circuit energizes the relay 43 and provides a locking circuit for the escapement magnet 45 to prevent said magnet from deenergizing and permitting the side switch to pass from 70 second to third position, when the relay 49 deenergizes after the last impulse for the second digit is delivered. The closure of the contact 169 of the relay 43 forms a locking circuit for said relay, said circuit extending 75 from ground G³ at the relay 48 through the springs 92 and 93, contact 170 of the relay 118, contact 169 and the lower winding of the relay 43 to the battery lead 90. The closure of the contact 171 upon the energization 80 of the relay 43 connects ground G¹² with the contacts 173 and 174 in the row which is engaged by the wiper 39. When the subscriber's calling device is operated for the third digit 2, the selected third selector in the main office will be operated in the usual manner to select an idle trunk line in its second level, which, in the case assumed, would be a trunk line leading back to a connector switch in the same exchange as 90 the calling subscriber. At the repeater L', since the side switch did not pass to third position after the second digit was called, the shaft and wipers will be rotated two more steps by the impulses for this third 95 digit 2, whereby the wipers 35, 36, 37, 38 and 39 will be brought into engagement with the contacts 175, 176, 177, 178 and 174, respectively. The engagement of the wiper 37 with the contact 177 completes a circuit extending from ground G³ at the relay 48 through the springs 92 and 93, contact 170, wiper 37, conductor 242 and winding 179 of the secondary switch M' to the battery lead 90. Upon the energization of the winding 100 179, the switch M' operates in the same manner as explained for the switch H' in the previous connection to extend the connection from the trunk conductors 240 and 241 to an idle connector switch in the branch 110 office which has access to all the subscribers' lines whose numbers begin with 1-1-2. The engagement of the wiper 39 at the repeater with the contact 174 completes a circuit extending from ground G¹² at the 115 relay 43 (which is locked in its operated position) through the contact 171, contact 174, wiper 39, relay 47 and side switch wiper 44 (which passed to third position after the third digit was called) to the battery lead 120 90. The relay 47, by shifting the springs 87 and 84 out of engagement with their back contacts and into engagement with their front contacts, disconnects the calling line from the line relay 33 of the repeater L' and 125 extends the line connection through the wipers 35 and 36 and contacts 175 and 176 to the trunk conductors 240 and 241, which, as has been explained, are now connected to an idle connector switch which has access to the 130

lines of the desired subscriber. When the line is disconnected from the line relay of the repeater L' by the relay 47, said line relay deenergizes and destroys the energizing circuit for the line relay of the connector to which the connection has been extended by the selectors in the main office, whereby said selectors are permitted to release in essentially the same manner in which the selectors 5 circuit for the line relay of the connector to which the connection has been extended by the selectors in the main office, whereby said selectors are permitted to release in essentially the same manner in which the selectors 10 were released by the deenergization of the line relay of the connector F' when the subscriber at substation T^2 was called. The breaking of the contact 98 by the energization of the relay 47 at the repeater L' de- 15 stroys the holding circuit of the secondary switch H' (Fig. 4), whereby said switch is released and frees the trunk line leading to the selector I' . It will thus be seen that when the subscriber calls the third digit, not 20 only is all the apparatus in the main office released, but also the trunk line leading from the branch office to the main office. The operations of the switches in the main office in connection with this call are merely inci- 25 dental and have no direct function in the establishment of the connection. The subscriber's line conductors are now extended from the line switch E' through the contacts of the relay 47, thence through the wipers 30 35 and 36, conductors 240 and 241, secondary switch M' and over the trunk conductors 180, 181 and 182 to a connector switch which has access to the line of the desired subscriber, which connector may in all respects 35 be the same as the connector F' (Fig. 6). When connection is extended to this connector its line relay energizes and provides a holding circuit for the switches M' and E' and for the relays 43 and 118 of the repeater L' . Said circuit extends from a ground at the connector which corresponds to ground G^{13} (Fig. 6) through the side switch wiper 162, contact 183, thence to the trunk-release conductor, such as the conductor 40 45 135 in Fig. 6 or the conductor 182 in Fig. 7, contact 185, thence one branch passes through the windings 179 and 186 of the switch M' to battery, while another branch passes back over the conductor 242 to the contact 177 and wiper 37 (Fig. 3), where it again branches, one branch passing back to and through the holding winding 97 of the switch E' , while another branch passes through the contact 169 of the relay 43, 50 55 (which, as before explained, is now energized) and through the lower winding of said relay to the battery lead 90. A third branch of this circuit extends from the wiper 37 through the contact 170 and winding of the relay 118 to the battery lead 90. This circuit serves to maintain the various relays and magnets included therein in an energized position after their original energizing circuits have been broken by the deenergiza- 60 65 tion of the slow acting relay 48 at the re-

peater L' , which occurs shortly after the circuit of said relay is broken by the deenergization of the repeater line relay 33.

The calling subscriber now operates his calling device for the last two digits of the 70 number of the called subscriber, which causes the selected local connector to establish connection with the desired line in the same manner as explained for the connector F' (Fig. 6), when the subscriber at substa- 75 tion T^2 was called. After the conversation is completed, the connection is released by the hanging up of the receiver at the calling substation in the usual manner—that is, when the receiver is restored to the switch 80 hook, the line relay of the connector switch deenergizes and releases the connector in the manner hereinbefore described and removes the ground connection from the conductor 182 (Fig. 7). This destroys the holding cir- 85 cuits of the switches M' and E' and of the relays 43 and 118 of the repeater L' . The switches M' and E' are thereupon restored to their normal positions. The relay 43, upon deenergizing, breaks the energizing 90 circuit of the relay 47 of the repeater L' . The relay 118, upon deenergizing, closes the circuit of the release magnet 46 in a manner which has previously been described, whereby the shaft and side switch of said 95 repeater are restored to normal position.

In the selector-repeater L' there are provided means for giving the calling subscriber a busy signal in case all the trunk lines leading from the secondary switch H' 100 to the main exchange are in use when the call is initiated. This means comprises the double-wound relay 112 in the selector-repeater. The upper winding of the relay 112 is bridged across the trunk conductors 30 105 and 31 by the closure of the line relay springs 111 when the call is initiated. If any of the trunk lines to which the switch H' has access are idle, a connection will be extended to said trunk line and the relay 112 110 will be energized, as has heretofore been explained, and will open the contact 117. If, however, all the trunk lines to which the switch H' has access are busy, its master switch N' will be operated continuously and 115 the contact 103 will be open. Therefore, the switch H' will not be operated when connection is extended to it through the repeater L' by the subscriber's individual switch E' . This being the case, the relay 112 in the repeater will not be energized. It will thus be seen that as soon as the relay 118 is energized a circuit is closed extending from ground G^{19} through the spring 166 and its front contact springs 117 and the lower 120 winding of the relay 112 to the busy signaling machine Q . The busy signaling current flowing through the lower winding of this relay induces a corresponding current in the upper winding, which, being bridged across 125 130

the subscriber's line, transmits a signal to the calling subscriber.

In the foregoing description it has been assumed that the selector-repeater is used in a one hundred thousand line system, or a system in which the subscribers' numbers comprise five digits. It has also been assumed that the branch offices have a capacity of less than a thousand lines. In Fig. 8 5 there is represented the manner in which the contacts of the selector-repeater F would be connected up in a branch office of four hundred line capacity. Assuming that the wipers normally rest one step below their respective rows, the branch office numbers with the connections as shown would be 111XX, 112XX, 114XX and 115XX. The second digit of all these numbers is 1, which is indicated by the fact that the first contact in the 10 row *c* which is engaged by the wiper 38 is connected to the relay 43. The third digit may be either 1, 2, 4 or 5, which is indicated by the fact that the contacts in the row *b* which are connected to the contact 171 of the 15 relay 43 are the first, second, fourth and fifth contacts, which are engaged by the wiper 39 after the wiper 38 leaves the contact in the row *c* which is connected to the winding of the relay 43. If there were only one hundred-group in the branch office, only one contact in the row *b* would be connected to the contact 171, and only one set of contacts in the rows, *d*, *e* and *f* would be connected to a secondary switch M', or, if desired, the 20 conductors leading to the switch M' (conductors 240 and 241, Fig. 3) could be permanently connected to the conductors 275 and 276, and the wipers 35 and 36 and contacts *e* and *f* entirely dispensed with in this 25 25 particular case. If there are more than four hundred-groups in the branch office, more than four contacts in the row *b* would be connected to the contact 171. If the capacity were increased to one thousand lines, 30 ten of the contacts could thus be connected and the connections handled in the same manner as hereinabove described. If an entire thousand numbers be allotted to the branch office, the connections, however, could 35 be taken care of in a much simpler manner. Assuming that a thousand numbers are assigned to the local office, it is evident that it is determined whether or not the calling subscriber intends to call back into his own 40 office as soon as he calls the second digit. This being the case, the connection could be switched to the local switch as soon as the second digit was called. In this case the connection would be switched to a secondary 45 switch M' which has access, not to connector switches, but to selector switches, which would operate in response to the impulses for the third digit in the same manner as the third selectors in the main office to select an 50 idle connector, through which connection 55

could be completed with the desired line. If there were more than one complete thousand numbers in the branch office, a plurality of trunk lines would be connected to the contacts which are engaged by the wipers 35, 36 and 37, and each of these trunks would lead to a switch M' which had access to selector switches, which latter in turn had access to different groups of connector switches. In Fig. 9 there are represented the connections 70 of the banks of the selector-repeaters in a branch office to which are assigned four thousand numbers. Since in this case the selector-repeater operates in response to only two digits, there is no need of a wiper corresponding to the wiper 38, or a relay corresponding to the relay 43. In the row *b'* which is engaged by the wiper 39 the contacts which correspond to the groups of lines in the branch office are permanently grounded. Therefore, assuming that the wipers in Fig. 9 normally rest one step below their respective rows of contacts, the connections in this figure are arranged for a branch office in which the subscribers' numbers are 80 85 11XXX, 12XXX, 14XXX and 15XXX. In this instance it would be necessary for the shaft of the selector-repeater to have only ten rotary steps. This arrangement of the selector-repeater is also adapted for branch 90 offices of one thousand lines, or smaller capacity, in a ten thousand line system. In such a system the connections, as shown in Fig. 9, would be suitable for an office to which were allotted the numbers 11XX, 100 12XX, 14XX and 15XX.

In case all the numbers which begin with any certain digit are allotted to one branch office, then the switching repeater should be arranged to switch to the local switch 105 only when one digit is called, and the secondary switches M would have access to selector switches which could perform the function of second selectors in an ordinary system. The selector-repeater may be arranged to switch on the first digit by giving the switch shaft rotary motion only and giving the side switch wiper 44 only two positions, the contacts of which wiper would be connected in the same manner as the contacts for the second and third positions of the wiper 44 in Fig. 3. The vertical magnet would be dispensed with and there would be no need for contact in the side switch wiper corresponding to the first position contact 110 115 point of the wiper 44 (Fig. 3). In Fig. 10 there is represented the connections of the contacts of a selector-repeater arranged for use in a branch office to which are allotted the numbers 1XXXX and 2XXXX in a 120 one-hundred thousand line system, or numbers 1XXX and 2XXX in a ten-thousand line system.

It will be seen that the switching relay 47 in the repeater L' is placed in front of the 130

line relay, as well as in front of the condensers 28 and 29. It is thus seen that not only are the two impedance bridges of the repeater excluded from the local connections, but there is also a conductively continuous circuit from the calling line through the secondary switch M' to whatever additional switches are employed in the local connections. This exclusion of the repeater from the local connections has especial advantage in case party lines are used in the system. Although in the system shown herein the act of signaling the called subscriber is accomplished automatically without the control of the calling subscriber after connection is completed between two lines, with most methods of signaling back on the calling line, in case of a reverting call on a party line, the application of the ringing current to the line must be controlled by the calling subscriber. This control may be accomplished much more simply if no condensers are included in the line between the substation and the signaling apparatus than if condensers are included. To illustrate this feature of the invention, we have shown in Fig. 11 a so-called ring-back device for use in signaling called subscribers in reverting calls on party lines. One or more of these ring-back devices may be placed in the branch office and made accessible through secondary switches M' which are connected to some particular contacts in the switching repeaters L' . Each party-line subscriber would then be informed that in order to call any other subscriber on his own line he must call a special number corresponding to the contact in the repeaters L' to which the secondary switches M' , which have access to the ring-back devices, are connected. The ring-back device shown in Fig. 11 is similar to that shown and described in British patent to S. G. S. Dicker No. 1428 of 1910, and comprises essentially a pair of wipers 201 and 202 carried upon a rotary shaft (not shown) which is adapted to be rotated step by step by a driving magnet 211 and released to normal position by a release magnet 225. The wipers 201 and 202 are adapted to contact with a plurality of pairs of stationary contacts which form the terminals of a plurality of ringing current generators O', O^2, O^3, O^4 , each of which is adapted to produce ringing current of a proper character for operating the ringer of some one substation on each of the party lines. The ring-back device is also provided with a two-position auxiliary or side switch comprising the wipers 203, 204 and 214, and which is controlled by an escapement magnet 218 in the same manner in which the private magnets of the selector and connector switches control their side switches. In order to call a substation on his own line, a calling subscriber, after removing his receiver, first operates his calling device for the proper digits to cause the selector-repeater to extend connection through one of the secondary switches M' to one of these ring-back devices in the same manner in 70 which connection is extended to a connector switch by the secondary switch M' (Fig. 7) in the connection heretofore explained. When the connection is extended to the ring-back device, its line relays 210 and 209 become energized in the same manner in which the line relay of the connector is energized when connection is extended to it. The relay 210, upon energizing, closes the circuit of the relay 217, which in turn connects 80 ground to the holding trunk 255 to furnish a holding circuit for the preceding apparatus in the connection. The calling subscriber must now operate his calling device for one more digit to cause the wipers 201 and 202 85 to be brought into contact with the proper generator for ringing the station desired. The relays 210 and 209 respond in the usual manner to the operation of the calling device for this digit, the relay 210 operating 90 to transmit one or more impulses over the circuit extending from ground G^{16} through the contacts 262 and 264, relay 212, stepping magnet 211 and the side switch wiper 204 to the battery lead 90. The magnet 211 operates in response to these impulses to move the wipers 201 and 202 onto the desired contacts, while the relay 212 operates in a well-known manner to cause the escapement magnet 218 to advance the side switch to its 95 second position after the last impulse for the digit is transmitted. In passing from first to second position the side switch wiper 203 cuts off the line relay 210 and substitutes therefor the relay 218, which operates to 100 maintain the circuit of the relay 217 closed. In order to cause the selected ringing current generator to be connected with the line, the calling subscriber depresses a button at his telephone, such as the button 265 (Fig. 110 3), for example. The depression of this button inserts an additional resistance in the line circuit, whereby the current in the line is reduced sufficiently to cause the relay 209 (Fig. 11) to allow its armature to drop back, 115 while the relay 218 remains in its energized position. The relay 209, upon deenergizing, completes a circuit extending from ground G^{18} through the interrupter 220, contact 272, ringing relay 219 and the side switch wiper 120 204 to the battery lead 90. The relay 219 is intermittently energized over this circuit and in its energized position operates to disconnect the relay 209 from the line to substitute therefor a connection to ground 125 through the resistance 221 to maintain the circuit of the relay 218, and also connects the selected ringing current generator with the calling line. Ringing current will continue to be periodically supplied to said line 130

until either the calling subscriber releases his ringing button, or until the called subscriber answers, in either of which cases the relay 209 will again be supplied with sufficient current to be operatively energized to break the circuit of the ringing relay. When both subscribers hang up their receivers after the conversation is completed, both the relays 218 and 209 deenergize. The relay 218, upon deenergizing, breaks the circuit of the relay 217, which in turn, upon deenergizing, closes the circuit of the release magnet 225. This circuit extends from ground G¹⁶ through the contact 262 of the relay 210, contact 279, magnet 225 and the contact 224 to the battery lead 90. The magnet 225, upon energizing, immediately restores the wipers 201 and 202 to normal position, whereupon the shaft-controlled contact 224 is opened and the magnet 225 permitted to deenergize. The apparatus through which connection is extended to the ring-back device is released in the manner heretofore explained when the holding ground is removed from the conductor 255 by the relay 217.

In the above description it is seen that in order to cause the ringing current to be applied to the line the calling subscriber must in some manner decrease the current flowing in the relay 209 of the ring-back device. If there are no condensers between the calling line and said device, as in the present case, this may be done by simply inserting a resistance in the line at the substation, as has been explained, while if the condensers of the repeater were included in this connection additional means would have to be supplied by which this control of the ring-back device could be accomplished.

It will thus be seen that we have devised a very efficient arrangement for district telephone systems. That as soon as it is determined by a process of elimination that the called subscriber is in the same branch office as the calling subscriber, then the connection which has heretofore been established to the main office is released and the connection completed over connections local to the branch office. In other words, the connection is first extended over two parallel paths and then at a certain point, when it has been determined that the connection is a local connection, one path is cut off and the connection completed over the other path.

While we have illustrated and described our invention in connection with an automatic telephone system of a particular type, it will be understood that in its broader aspect our invention is capable of use with other automatic systems, or in semi-automatic systems—that is, systems in which a manual operator is employed for setting up certain parts of a connection. Various modifications in the repeater which is em-

ployed to repeat the impulses from the branch to the main office will likewise readily suggest themselves to those skilled in the art but come within the scope of our invention.

What we claim as our invention is:

1. In a telephone system, a plurality of branch exchanges, subscribers' lines connected with said branch exchanges, means for establishing a connection between two of said subscribers' lines, said means including a trunk line having a terminal in a branch exchange, a branch for said trunk extending toward the main exchange, a local branch for said trunk normally disconnected therefrom, and means for connecting the local branch when a call is made by a subscriber in the same branch exchange, and for disconnecting the main branch during talking.

2. In a telephone system, subscribers' lines divided into groups, a trunk having a single terminal at one end thereof, a branch normally connected to said terminal and extending toward a plurality of said groups, a second branch normally disconnected from said trunk and extending toward other of said groups, and means for disconnecting said normally connected branch and connecting said other branch when it is desired to extend a connection to the particular groups to which said other branch is connected.

3. In a telephone system, a switch, a plurality of trunks leading therefrom, an automatic means associated with said switch for automatically switching a connection from a given trunk to another, automatic apparatus associated with said given trunk, and means in said switch for initiating a release of said automatic apparatus.

4. In a telephone system, main and branch exchanges, subscribers' lines connected to said branch exchanges, trunking apparatus at said exchanges, means whereby a subscriber in making a call operates said apparatus to first determine the main exchange and then the branch exchange with which the desired called subscriber's line is connected, a trunk leading to the trunking apparatus in one exchange, a second trunk leading to the trunking apparatus in another exchange, and means at one of the exchanges for initiating and causing a release of the trunking apparatus in the other exchange when the trunking operations have reached a stage of eliminating said exchange, which trunking apparatus was brought into use over said trunk.

5. In a telephone system, main and branch exchanges, subscribers' lines connected with said branch exchanges, trunking apparatus at said exchanges, means whereby a subscriber in making a call operates said apparatus to first determine the main exchange and then the branch exchange with which

the desired called subscriber is connected, a trunk at a branch exchange leading to the trunking apparatus at a main exchange, a second trunk in the same branch exchange 5 leading to trunking apparatus in that exchange and normally disconnected from said trunking apparatus, means whereby a subscriber at said branch exchange, when initiating a call, first extends a connection over 10 the trunk extending to said main exchange, and means for then breaking said connection and extending the connection over said local trunk when it is determined that the call is for a subscriber in the same branch 15 exchange.

6. In a telephone system, main and branch exchanges, subscribers' lines connected with said branch exchanges, trunking apparatus at said exchanges, means whereby a subscriber 20 in making a call operates said apparatus to first determine the main exchange and then the branch exchange with which the desired called subscriber is connected, a trunk at a branch exchange leading to the 25 trunking apparatus at a main exchange, a second trunk in the same branch exchange leading to trunking apparatus in that exchange and normally disconnected from said trunking apparatus, means whereby a subscriber 30 at said branch exchange, when initiating a call, first extends a connection over the trunk extending to said main exchange, means for then breaking said connection and extending the connection over said local 35 trunk when it is determined that the call is for a subscriber in the same branch exchange, and means for releasing the switching apparatus at the main exchange when the connection is shifted to the local trunk.

40 7. In a telephone system, a trunk line having a single terminal at one end thereof and a pair of branches, one normally connected with said terminal and the other normally disconnected therefrom, a repeating 45 mechanism in said normally connected branch, means controlled by said repeating mechanism for repeating impulses received over said terminal, and means controlled by said repeater for disconnecting said normally connected branch from said terminal and connecting said normally disconnected branch thereto when a particular sequence of impulses is received by said repeater.

8. In a telephone system, a trunk line 55 having a single terminal at one end thereof and a pair of branches, one normally connected with said terminal and the other normally disconnected therefrom, switching mechanism associated with said trunk, a 60 pair of line wipers and a pilot wiper for said switching mechanism, means for transmitting a plurality of series of impulses over said trunk to operate said mechanism, and means controlled by said mechanism 65 when said pilot wiper has been moved in

response to certain combinations of impulses to shift the connection of said terminal to the normally disconnected branch of the trunk.

9. In a telephone system, a trunk line 70 having a single terminal at one end thereof and a pair of branches, one normally connected with said terminal and the other normally disconnected therefrom, a repeating mechanism in said trunk, said repeating 75 mechanism including line and pilot wipers, means for operating said repeating mechanism by impulses received over said trunk to move said wipers, means controlled by said repeater for repeating impulses over 80 one branch of the trunk, and means controlled by said pilot wiper, when it has been moved in response to a certain sequence of impulses, to switch the connections from said trunk terminal to the normally disconnected 85 branch of the trunk.

10. In a telephone system, trunk lines having a single terminal at one end thereof and a pair of branches, one normally connected with said terminal and the other normally disconnected therefrom, a switching mechanism in said trunk, line and pilot wipers controlled by said mechanism, bank contacts with which said wipers are adapted to engage, a relay operatively connected 90 with certain of the contacts in the bank engaged by said pilot wiper, means for energizing said relay when said pilot wiper comes in contact with said contacts, means operated by the energization of said relay 95 for shifting the connection of said trunk terminal to the normally disconnected branch of the trunk, and means controlled by said switching mechanism for repeating 100 the impulses, received over said trunk terminal, over the normally connected branch of the trunk.

11. In a telephone system, a main exchange, a branch exchange, subscribers' lines terminating at said branch exchange, a 110 trunk line having a terminal adapted to be connected with said subscribers' lines and provided with two branches, one extending toward the main exchange and the other extending toward switching mechanism in said 115 branch exchange, impulse-transmitting devices on said subscribers' lines, a repeater in said trunk for repeating impulses over said trunk toward the main exchange, said repeater including a pair of line wipers and 120 a pilot wiper, means for transmitting a plurality of series of impulses over said trunk to operate said repeater, and means controlled by said repeater when said pilot wiper has been moved in response to certain 125 combinations of impulses to shift the connections of said trunk terminal from the branch extending toward the main exchange.

12. In a telephone system, a main exchange, a branch exchange, subscribers' lines 130

- terminating at said branch exchange, a trunk line having a terminal adapted to be connected with said subscribers' lines and provided with two branches, one extending 5 toward the main exchange and the other extending toward switching mechanism in said branch exchange, impulse-transmitting devices on said subscribers' lines, a repeater in said trunk for repeating impulses over said 10 trunk toward the main exchange, said repeater including line and pilot wipers, means for operating said repeater by impulses received over said trunk to move said wipers, means controlled by said repeater 15 for repeating impulses over a branch of the trunk to the main exchange, and means controlled by said pilot wiper when it has been moved in response to a certain sequence of impulses to switch the connections from said 20 trunk terminal to the normally disconnected local branch of the trunk.
13. In a telephone system, a main exchange, a branch exchange, a plurality of groups of subscribers' lines, a trunk at said 25 branch exchange extending toward said main exchange, a second trunk local to said branch exchange, means by which a calling subscriber in establishing a connection with a called subscriber in the same exchange first 30 extends such connection over the trunk extending toward the main exchange and then shifts the connection to the local trunk and disconnects said main trunk, and a non-numerical trunk-selecting switch in said 35 local trunk and a group of numerical trunking switches an idle one of which is adapted to be selected by said non-numerical switch for extending the connection to the called line.
14. In a telephone system, subscribers' lines, a main and a branch exchange, a connecting circuit in said branch exchange, repeating mechanism in said circuit, a trunk line leading from said branch to said main 45 exchange, a trunk local to said branch exchange, means controlled by a subscriber in making a call for connecting his line with said connecting circuit, an impulse transmitter for transmitting impulses over said line, means 50 controlled by said repeating mechanism for repeating said impulses to the main exchange, automatic switches at the main exchange operated by said impulses, and means controlled by the repeater for disconnecting 55 said main exchange trunk and said automatic switches from said subscriber's line and connecting said branch exchange trunk with the line, whereby said main exchange trunk and said automatic switches are released 60 when it is desired to make connection with a subscriber in the same branch exchange.
15. In a telephone system, subscribers' lines a main and a branch exchange, a connecting circuit in said branch exchange, repeating 65
- mechanism in said circuit, a plurality of trunk lines leading from said branch to said main exchange, a trunk line local to said branch exchange, means for connecting a calling subscriber's line with said connecting 70 circuit, a non-numerical switch in said connecting circuit for selecting an idle trunk extending to said main exchange, automatic switches in said main exchange, an impulse transmitter on said subscriber's line for 75 transmitting impulses over the subscriber's line, means controlled by said repeater to repeat said impulses over the trunk to the main exchange to thereby operate said automatic switches, and means controlled by said repeater for disconnecting said main exchange trunk from the subscriber's line to thereby release said automatic switches and to connect said local trunk with the line when it is desired to make connection with 80 a called subscriber whose line terminates in the same branch exchange.
16. In a telephone system, subscribers' lines, a main and a branch exchange, a connecting circuit in said branch exchange, repeating mechanism in said circuit, a trunk line leading from said branch to said main exchange, means for connecting said trunk with said connecting circuit, a trunk local to said branch exchange, means for connecting 90 a calling line with said connecting circuit, means controlled by said repeating mechanism for then extending connection to said main exchange over said main exchange trunk, means for then controlling said repeater to cause it to disconnect said main exchange trunk and connect said branch exchange trunk with the subscriber's line when it is desired to make connection with a subscriber in the same branch exchange, automatic 95 trunk-selecting switches in said branch exchange for extending a connection to a called line, and a non-numerical trunk-selecting switch in said local trunk for selecting an idle one of said trunk-selecting 100 switches when said local trunk is seized.
17. In a telephone system, subscribers' lines, a main and a branch exchange, a connecting circuit at said branch exchange, repeating mechanism in said circuit, a plurality 105 of trunk lines leading from said branch to said main exchange, a plurality of trunk lines local to said branch exchange for use in establishing connection between subscribers' lines which terminate in said branch exchange, means for connecting a calling line with said connecting circuit, a non-numerical trunk-selecting switch in said connecting circuit for then extending the connection over an idle trunk to said main 115 exchange, automatic switching mechanism at said main exchange, means for then transmitting impulses to said repeater, means whereby said repeater then repeats said impulses over the trunk to the switches at the 120
- 130

- main exchange to thereby operate the same, means controlled by said repeater for disconnecting said main exchange trunk from the line and connecting one of said local trunks thereto when it is desired to establish connection with a subscriber in the same branch exchange, a non-numerical trunk-selecting switch in said local trunk, automatic switches in said branch exchange for completing the connection to the called line, and means controlled by said last-mentioned non-numerical trunk-selecting switch for selecting an idle one of said branch exchange automatic switches.
18. In a telephone system, subscribers' lines, a main and a branch exchange, a connecting circuit in said branch exchange, repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending connection to said main exchange over said main exchange trunk, said repeating mechanism including line and pilot wipers and means for controlling the same, bank contacts with which said wipers are adapted to engage, a relay operatively connected with certain of the contacts in the bank engaged by said pilot wiper, means on the calling subscriber's line for transmitting impulses to said repeater to operate said wipers over said bank contacts, means for energizing said relay when said pilot wiper comes in contact with the particular contact connected with said relay, and means operated by the energization of said relay for disconnecting said main exchange trunk from the subscriber's line and connecting said branch exchange trunk thereto.
19. In a telephone system, subscribers' lines, a main and a branch exchange, a connecting circuit in said branch exchange, repeating mechanism in said circuit, trunk lines extending from said branch to said main exchange, a trunk local to said branch exchange, means controlled by a subscriber in making a call for connecting his line with said connecting circuit, a non-numerical trunk-selecting switch at one end of said connecting circuit controlled by said repeating mechanism for selecting an idle trunk to said main exchange to thus extend the connection from the calling subscriber's line to the main exchange, said repeating mechanism including line and pilot wipers and means for controlling the same, bank contacts with which said wipers are adapted to engage, a relay operatively connected with certain of the contacts in the bank engaged by said pilot wiper, means on the calling subscriber's line for transmitting impulses to said repeater to operate said wipers over said bank contacts, means for energizing said relay when said pilot wiper comes in contact with the particular contact connected with said relay, and means operated by the energization of said relay for disconnecting said main exchange trunk from the subscriber's line and connecting said branch exchange trunk thereto, whereby said main exchange trunk and said automatic switches are released when it is desired to make connection with a subscriber in the same branch exchange.
20. In a telephone system, subscribers' lines, a main and a branch exchange, a connecting circuit in said branch exchange, repeating mechanism in said circuit, a trunk line leading from said branch to said main exchange, a trunk local to said branch exchange, means controlled by a subscriber in making a call for connecting his line with said connecting circuit, an impulse transmitter for transmitting impulses over said line, means controlled by said repeating mechanism for repeating said impulses to the main exchange, automatic switches at the main exchange operated by said impulses, said repeating mechanism including line and pilot wipers and means for controlling the same, bank contacts with which said wipers are adapted to engage, a relay operatively connected with certain of the contacts in the bank engaged by said pilot wiper, means on the calling subscriber's line for transmitting impulses to said repeater to operate said wipers over said bank contacts, means for energizing said relay when said pilot wiper comes in contact with the particular contact connected with said relay, and means operated by the energization of said relay for disconnecting said main exchange trunk from the subscriber's line and connecting said branch exchange trunk thereto, whereby said main exchange trunk and said automatic switches are released when it is desired to make connection with a subscriber in the same branch exchange.
21. In a telephone system, subscribers' lines, a main and a branch exchange, a connecting circuit in said branch exchange, repeating mechanism in said circuit, a plurality of trunk lines leading from said branch to said main exchange, a trunk line local to said branch exchange, means for connecting a calling subscriber's line with said connecting circuit, a non-numerical switch in said connecting circuit for selecting an idle trunk extending to said main exchange, automatic switches in said main exchange, an impulse transmitter on said subscriber's line for transmitting impulses over the subscriber's line, means controlled by said repeater to repeat said impulses over the trunk to the main exchange to thereby operate said automatic switches, said repeating mechanism including line and pilot wipers and means for controlling the same, bank contacts with which said wipers are adapted to engage, a relay operatively con-

nected with certain of the contacts in the bank engaged by said pilot wiper, means on the calling subscriber's line for transmitting impulses to said repeater to operate said 5 wipers over said bank contacts, means for energizing said relay when said pilot wiper comes in contact with the particular contact connected with said relay, and means operated by the energization of said relay 10 for disconnecting said main exchange trunk from the subscriber's line and connecting said branch exchange trunk thereto, whereby said main exchange trunk and said automatic switches are released when it is desired 15 to make connection with a subscriber in the same branch exchange.

22. In a telephone system, subscribers' lines, a main and a branch exchange, a connecting circuit in said branch exchange, repeating mechanism in said circuit, a plurality of trunk lines leading from said branch to said main exchange, a trunk line local to said branch exchange, means for connecting a calling subscriber's line with 20 said connecting circuit, a non-numerical switch in said connecting circuit for selecting an idle trunk extending to said main exchange, automatic switches in said main exchange, an impulse transmitter on said subscriber's line for transmitting impulses over 25 the subscriber's line, means controlled by said repeater to repeat said impulses over the trunk to the main exchange to thereby operate said automatic switches, said repeating mechanism including line and pilot wipers and means for controlling the same, bank contacts with which said wipers are 30 adapted to engage, a relay operatively connected with certain of the contacts in the bank engaged by said pilot wiper, means on the calling subscriber's line for transmitting impulses to said repeater to operate said wipers over said bank contacts, means for energizing said relay when said pilot wiper comes in contact 35 with the particular contact connected with said relay, means operated by the energization of said relay for disconnecting said main exchange trunk from the subscriber's line and connecting said branch exchange 40 trunk thereto, a non-numerical trunk-selecting switch in said local trunk, automatic switches in said branch exchange for completing the connection to the called line, and means controlled by said last-mentioned 45 non-numerical trunk-selecting switch for selecting an idle one of said branch exchange 50 automatic switches.

40. In a telephone system, subscribers' lines, a main and a branch exchange, a connecting circuit in said branch exchange, repeating mechanism in said circuit, a trunk line leading from said branch to said main exchange, means for connecting said trunk with said connecting circuit, a trunk local 55 to said branch exchange, means for connecting a calling line with said connecting circuit, means controlled by said repeating mechanism for then extending connection to said main exchange over said main exchange 60 trunk, said repeating mechanism comprising a pair of line wipers and a pilot wiper, means controlled by the calling subscriber to transmit impulses in accordance with the digits of the called number, means controlled 65 by said impulses for moving said wipers in a vertical plane and then rotating the same, bank contacts with which said wipers engage, a relay operatively connected with certain of the contacts in one level of the bank 70 engaged by said pilot wiper, means for closing a circuit through said relay when said pilot wiper is stepped up to the proper level, and then rotated to engage the contacts connected with said relay, and means controlled 75

branch to said main exchange, a plurality of trunk lines local to said branch exchange for use in establishing connection between subscribers' lines which terminate in said branch exchange, means for connecting a 80 calling line with said connecting circuit, a non-numerical trunk-selecting switch in said connecting circuit for then extending the connection over an idle trunk to said main exchange, automatic switching mechanism at 85 said main exchange, means for then transmitting impulses to said repeater, means whereby said repeater then repeats said impulses over the trunk to the switches at the main exchange to thereby operate the same, 90 said repeating mechanism including line and pilot wipers and means for controlling the same, bank contacts with which said wipers are adapted to engage, a relay operatively connected with certain of the contacts in the bank engaged by said pilot wiper, said repeater responsive to said impulse transmitting means to operate said wipers over said bank contacts, means for energizing said relay when said pilot wiper comes in contact 95 with the particular contact connected with said relay, means operated by the energization of said relay for disconnecting said main exchange trunk from the subscriber's line and connecting said branch exchange 100 trunk thereto, a non-numerical trunk-selecting switch in said local trunk, automatic switches in said branch exchange for completing the connection to the called line, and means controlled by said last-mentioned 105 non-numerical trunk-selecting switch for selecting an idle one of said branch exchange 110 automatic switches.

24. In a telephone system, subscribers' lines, a main and a branch exchange, a connecting circuit in said branch exchange, repeating mechanism in said circuit, a trunk line leading from said branch to said main exchange, means for connecting said trunk with said connecting circuit, a trunk local 115 to said branch exchange, means for connecting a calling line with said connecting circuit, means controlled by said repeating mechanism for then extending connection to said main exchange over said main exchange 120 trunk, said repeating mechanism comprising a pair of line wipers and a pilot wiper, means controlled by the calling subscriber to transmit impulses in accordance with the digits of the called number, means controlled 125 by said impulses for moving said wipers in a vertical plane and then rotating the same, bank contacts with which said wipers engage, a relay operatively connected with certain of the contacts in one level of the bank 130 engaged by said pilot wiper, means for closing a circuit through said relay when said pilot wiper is stepped up to the proper level, and then rotated to engage the contacts connected with said relay, and means controlled 135

23. In a telephone system, subscribers' lines, a main and a branch exchange, a connecting circuit at said branch exchange, repeating mechanism in said circuit, a plurality of trunk lines leading from said

by the energization of said relay to disconnect the trunk leading to the main exchange from the calling line and for connecting the local trunk thereto.

5. 25. In a telephone system, subscribers' lines, a main and a branch exchange, a connecting circuit in said branch exchange, repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending connection to said main exchange over said main exchange trunk, a relay in said repeating mechanism, impulse-transmitting means on the calling line for transmitting impulses in accordance with the digits of the called number to extend a connection to the called line, means for operating said repeater in response to said impulses, means controlled by said repeater when the same has been operated in response to a certain combination of impulses to close a circuit through said relay to energize the same, and means controlled by the energization of said relay for disconnecting said main exchange trunk from the subscriber's line and for connecting the branch exchange trunk thereto at a point in front of the condensers, whereby said condensers are excluded from the connection to the branch exchange trunk.
10. 26. In a telephone system, subscribers' lines, a main and a branch exchange, a connecting circuit in said branch exchange, condensers and repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending the connection to said main exchange over said main exchange trunk, said repeating mechanism including line and pilot wipers, bank contacts with which said wipers are adapted to engage, a relay operatively connected with certain of said contacts in the bank engaged by said pilot wiper, means controlled by the calling subscriber for transmitting impulses to extend connection to a called line, means controlled by said impulses for operating said line and pilot wipers over said contacts, means for energizing said relay when said pilot wiper comes in contact with the particular contacts connected with said relay, and means operated by the energizing of said relay to disconnect said main exchange trunk from the calling line and to connect the branch exchange trunk thereto at a point in front of said condensers, whereby said condensers are excluded from the connection to said branch exchange trunk.
15. 27. In a telephone system, subscribers' lines, a main and a branch exchange, a connecting circuit in said branch exchange, condensers in the opposite sides of said connecting circuit, repeating mechanism in said circuit, a trunk line leading from said branch to said main exchange, means for connecting said trunk with said circuit, a trunk local to said branch exchange, means for connecting a calling line with said connecting circuit, means controlled by said repeating mechanism for then extending said connection to said main exchange over said main exchange trunk, and means for then controlling said repeater to cause it to disconnect said main exchange trunk from the calling line and to connect said branch exchange trunk with said line at a point in front of said condensers, whereby said condensers are excluded from said connection to the branch exchange trunk.
20. 28. In a telephone system, subscribers' lines, a main and a branch exchange, a connecting circuit in said branch exchange, condensers and repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending the connection to said main exchange over said main exchange trunk, said repeating mechanism including line and pilot wipers, bank contacts with which said wipers are adapted to engage, a relay operatively connected with certain of said contacts in the bank engaged by said pilot wiper, means controlled by the calling subscriber for transmitting impulses to extend connection to a called line, means controlled by said impulses for operating said line and pilot wipers over said contacts, means for energizing said relay when said pilot wiper comes in contact with the particular contacts connected with said relay, and means operated by the energizing of said relay to disconnect said main exchange trunk from the calling line and to connect the branch exchange trunk thereto at a point in front of said condensers, whereby said condensers are excluded from the connection to said branch exchange trunk.
25. 29. In a telephone system, subscribers' lines, a main and a branch exchange, a connecting circuit in said branch exchange, repeating mechanism in said circuit, a trunk line leading from said branch to said main exchange, means for connecting said trunk with said connecting circuit, a trunk local to said branch exchange,

- to said branch exchange, means for connecting a calling line with said connecting circuit, means controlled by said repeating mechanism for then extending connection to 5 said main exchange over said main exchange trunk, said repeating mechanism comprising a pair of line wipers and a pair of pilot wipers, means controlled by the calling subscriber for rotating said wipers, a relay having an energizing circuit thereof open at two points, means for closing said circuit at one point when the pilot wipers are rotated a certain number of steps, means for holding the circuit closed at this point, means for 10 then closing the energizing circuit at the second point when said pilot wipers are rotated a certain number of additional steps, and means controlled by the energization of said relay for disconnecting said main exchange trunk from the calling line for connecting the branch exchange trunk thereto.
30. In a telephone system, subscribers' lines, a main and a branch exchange, a connecting circuit in said branch exchange, condensers in opposite sides of said connecting circuit, repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending the connection to said main exchange over said main exchange trunk, said repeating mechanism comprising a pair of line wipers and a pair of pilot wipers, means controlled by the calling subscriber for rotating said wipers, a relay having an energizing circuit thereof open at two points, means for closing said circuit at one point when the pilot wipers are rotated a certain number of steps, means for holding the circuit closed at this point, means for 15 then closing the energizing circuit at the second point when said pilot wipers are rotated a certain number of additional steps, and means controlled by the energization of said relay for disconnecting said main exchange trunk from the calling line for connecting the branch exchange trunk thereto.
35. In a telephone system, subscribers' lines, a main and a branch exchange, a connecting circuit in said branch exchange, condensers in the opposite sides of said circuit, repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending connection to said main exchange over said main exchange trunk, said repeating mechanism including a pair of line wipers and a plurality of pilot wipers, and means for moving said wipers vertically and then rotating the same, an impulse transmitter on the calling line for transmitting a plurality of series of impulses in accordance with the digits of the called number, a relay in said repeater having an energizing circuit normally open at two points, banks with which said pilot wipers engage, means for moving said wipers vertically in response to one series of impulses, means for then rotating said wipers in response to the next two series of impulses, means controlled by one of said pilot wipers whereby, when said wipers are raised to the proper level and then rotated a proper number of steps, the circuit of said relay will be closed at one point, means for then holding the circuit closed at this point, means controlled by a second of said pilot wipers, when said wiper is then rotated a certain additional number of steps to close 70 75 80 85 90 95 100 105 110 115 120 125 130
32. In a telephone system, subscribers' lines, a main and a branch exchange, a connecting circuit in said branch exchange, condensers in the opposite sides of said circuit, repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending connection to said main exchange over said main exchange trunk, said repeating mechanism including a pair of line wipers and a plurality of pilot wipers, and means for moving said wipers vertically and then rotating the same, an impulse transmitter on the calling line for transmitting a plurality of series of impulses in accordance with the digits of the called number, a relay in said repeater having an energizing circuit normally open at two points, banks with which said pilot wipers engage, means for moving said wipers vertically in response to one series of impulses, means for then rotating said wipers in response to the next two series of impulses, means controlled by one of said pilot wipers whereby, when said wipers are raised to the proper level and then rotated a proper number of steps, the circuit of said relay will be closed at one point, means for then holding the circuit closed at this point, means controlled by a second of said pilot wipers, when said wiper is then rotated a certain additional number of steps to close 130
31. In a telephone system, subscribers' lines, a main and a branch exchange, a connecting circuit in said branch exchange, repeating mechanism in said circuit, a trunk line leading from said branch to said main exchange, means for connecting said trunk with said connecting circuit, a trunk local to said branch exchange, means for connecting a calling line with said connecting circuit, means controlled by said repeating mechanism for then extending connection to 60 65

the circuit at the second point to thereby energize said relay, and means controlled by the energizing of said relay to disconnect said main exchange trunk and connect said branch exchange trunk with the calling line at a point in front of said condensers, whereby said condensers are excluded from said branch exchange trunk connection.

33. In a trunking system, a group of lines, switches for completing connections to said lines, a divided trunk line having two branches, means for making said trunk line accessible to any one of said lines, means for extending either of said branches to an idle one of said switches, means operable when one of said branches has been so extended for disconnecting the extended branch, and means for then extending the other branch to an idle one of said switches over a different path.

34. In a trunking system, a group of lines, switches for completing connections to said lines, a divided trunk line having two branches, means for making said trunk line accessible to any one of said lines, impulse controlled switching mechanisms for extending one of said branches to an idle one of said switches, means then operable for disconnecting the extended branch, and an automatic switch for then extending the other branch to an idle one of said switches.

35. In a trunking system, a group of lines, automatic switches for completing connections thereto, a trunk line, means for making said trunk line accessible to said lines, a normally connected branch of said trunk line, means including a plurality of serially related link circuits for extending said branch to an idle one of said switches, a second branch of said trunk line normally disconnected therefrom, means including a lesser number of link circuits for extending said second branch to an idle one of said switches, automatic switches associated with said first link circuit whereby a calling one of said group of lines may be extended via said first branch, and automatic means whereby the second branch is substituted for the first and is extended in its turn.

36. In a trunking system, a group of lines, a trunk line accessible to said lines, other groups of lines, a normally connected branch of said trunk line having access through the medium of automatic impulse controlled switching mechanisms to said other lines, a normally disconnected branch of said trunk line having access to said first lines, an impulse sending mechanism associated with a calling one of said first group of lines for controlling said switching mechanism, an impulse registering device associated with said trunk line for registering the impulses transmitted to said switching mechanisms, and means controlled by said device when it registers a certain predetermined series of

impulses for disconnecting said normally connected branch and for substituting the other branch therefor.

37. In a trunking system, a calling line, a group of lines, a second group of lines, mechanism for first connecting said calling line with one of said second lines and for thereafter eliminating said connected second line when the call is for one of said first group of lines, said mechanism being operable to connect with one of said first group of lines when said second group of lines are in use.

38. In a trunking system, a calling line, a group of lines, a second group of lines, mechanism for first connecting said calling line with one of said second lines and for thereafter eliminating said connected second line when the call is for one of said first group of lines, said mechanism also being operable to connect with one of said first group of lines when all of said second group of lines are in use.

39. In a trunking system, a line, a second line, a third line, mechanism for connecting said line with said second line and for thereafter disconnecting said second line and connecting said third line, said mechanism operable to connect said line with said third line in the event said second line is in use.

40. In a trunking system, a line, a second line, a third line, mechanism for connecting said line with said second line and for thereafter disconnecting said second line and connecting said third line, means for giving said line a busy signal when said second line is in use, said mechanism being also operable to connect said line with said third line in the event said second line is in use.

41. In a trunking system, a line, a second line, a third line, mechanism for first connecting said line with said second line and if the third line is desired, for thereafter disconnecting said second line and connecting said third line, said mechanism operable to connect said line with said third line in the event said second line is in use.

42. In a telephone system, a trunk line, a line accessible thereto, said trunk line comprising a normally connected branch and a second branch, lines accessible to each of said branches, means for first extending a connection through said normally connected branch over one of said lines and for thereafter connecting said second branch and disconnecting said connected branch, said means also operable to extend a connection over said second branch in the event all lines accessible to said connected branch are busy.

43. In a telephone system, a trunk line, a line accessible thereto, said trunk line comprising a normally connected branch and a second branch, lines accessible to each of said branches, switching mechanism for first extending a connection through said nor-

mally connected branch over one of said lines and for thereafter connecting said second branch and disconnecting said connected branch, said switching mechanism also operable to extend a connection over said second branch in the event all lines accessible to said connected branch are busy.

44. In an automatic telephone exchange system, a main office, a satellite office, interoffice trunk lines extending from said satellite to said main office, local trunk lines within said satellite, means for selecting an inter-office trunk upon the initiation of a call at said satellite, automatic switching mechanism for effecting connection between subscribers, controlling devices associated with said satellite for governing said switching mechanism, and discriminating means operated under the control of said controlling devices when manipulated in accordance with the number of the wanted subscriber, for completing a connection over said interoffice trunk or for releasing said interoffice trunk and selecting a local trunk and effecting a connection over said local trunk according to whether the wanted subscriber is located at an exchange exterior to said satellite or at said satellite.

45. In a telephone exchange system, a main office, a satellite office, trunk lines extending from said satellite to said main office and other trunk lines local to said satellite, a pair of trunk finders at said satellite, one for connecting the line of a calling subscriber at the satellite to an interoffice trunk and the other for connecting the line of the calling subscriber to a local trunk, and means whereby the interoffice trunk finder is actuated upon the initiation of all calls at the satellite and whereby the local trunk finder is actuated only when the calling and called subscribers are at the same satellite.

46. In a telephone exchange system, a main office, a satellite office, trunk lines extending from said satellite to said main office and other trunk lines local to said satellite, automatic switches for effecting connection between subscribers, a pair of trunk finders at said satellite through one of which talking connection is established from calling subscribers at the satellite to subscribers associated with the main office and through the other of which connection is established to subscribers at said satellite, controlling devices associated with said satellite for governing said switches, and means operated under the control of said controlling device when manipulated in accordance with the number of a wanted subscriber for selecting the necessary line finder and completing a talking connection therethrough.

47. In a telephone exchange system, a main office, a satellite office, interoffice trunk lines extending between said satellite and said main office and local trunk lines at said satel-

lite, automatic switching mechanism for effecting connection between subscribers, said mechanism including a pair of trunk finders at said satellite for said interoffice and local trunk lines respectively, through one of which trunk finders the line of the calling subscriber may be extended to subscribers at the main exchange and through the other to subscribers at the satellite, controlling devices associated with said satellite for governing said switches, and means operated under the control of said controlling devices when manipulated in accordance with the number of a wanted subscriber for completing a connection through the required one or the other of said trunk finders according to whether the wanted subscriber is located at the same satellite with the calling subscriber or at an exchange exterior thereto.

48. In a telephone exchange system, a main office, a satellite office, interoffice trunk lines between said satellite and said main office and local trunk lines at said satellite, automatic switching mechanism for effecting connection between subscribers, said mechanism including a pair of trunk finders at said satellite through one of which the line of a calling subscriber at the satellite may be extended through switching mechanism to subscribers at said satellite and through the other of which said calling line may be extended by main office switching mechanism to subscribers external to the said satellite, and means operating upon the initiation of a call at said satellite for automatically selecting and completing a connection through one or the other of said trunk finders according to whether the wanted subscriber is at the satellite or external thereto.

49. In a telephone exchange system, a main office, a satellite office, trunk lines extending from said satellite to said main office and other trunk lines local to said satellite, automatic switching mechanism for extending a connection from a satellite subscriber to other subscribers at said exchange, said switching mechanism including interoffice trunk finders and local trunk finders at said satellite, one of said interoffice trunk finders being actuated upon the initiation of all calls at said satellite to select an interoffice trunk, controlling devices for governing said switching mechanisms, and apparatus associated with said selected trunk operating under the control of a controlling device at the satellite when manipulated in accordance with the number of a wanted subscriber at said satellite to close a circuit, whereby means will be actuated to restore to normal said interoffice trunk finder, and complete a talking circuit between the calling and called subscribers through one of said local trunk finders.

50. In a telephone exchange system, a

main office, a satellite office, interoffice trunk lines from said satellite to said main office and local trunk lines at said satellite, automatic switching mechanism for effecting 5 connection between subscribers' lines, said mechanism including local trunk finders and interoffice trunk finders at said satellite and selectors at said main exchange, controlling devices associated with said satellite for 10 governing the operation of said switches, said interoffice trunk finders being actuated upon the initiation of all calls at the satellite to extend the line of the calling subscriber to a selector, and apparatus which is actuated upon the reception of certain series of 15 impulses from said controlling device to effect the operation of mechanism, whereby the interoffice trunk will be released and the local trunk finder will be operated to extend 20 the line of the calling subscriber to one of said local trunks through said local trunk finder.

51. In a telephone exchange system, a main office, a satellite office, trunk lines extending from said satellite to said main office and other trunk lines local to said satellite, automatic switching mechanism for extending 25 a connection from a satellite subscriber to other subscribers at said exchange, said switching mechanism including interoffice trunk finders and local trunks finders at said satellite and selectors at said main exchange, controlling devices for governing said switching mechanism, an interoffice trunk 30 finder being actuated upon initiation of all calls at the satellite to select a trunk to an idle selector at the main exchange, and apparatus associated with said selector trunk operating under the control of a controlling 35 device when manipulated in accordance with the number of a wanted subscriber at said satellite to close a circuit, whereby means will be operated to restore to normal the interoffice trunk finder and complete a talk- 40 ing circuit between the calling and called subscribers through said local trunk finder.

52. In a telephone exchange system, an office, a second office, interoffice trunk lines extending between said offices, other trunk 50 lines local to said second office, and means whereby upon the initiation of all calls at said second office the subscriber's line will be connected to an interoffice trunk and whereby the subscriber's line will be connected to a local trunk only when the calling and called subscribers are at said second office.

53. In a telephone exchange system, an office, a second office, interoffice trunk lines 60 extending between said offices, other trunk lines local to said second office, switching devices at said second office for connecting the line of a calling subscriber thereat to an interoffice trunk and to a local trunk respectively, and means whereby upon the initia- 65

tion of all calls at said second office the subscriber's line will be connected to an interoffice trunk and whereby the subscriber's line will be connected to the local trunk only when the calling and called subscribers 70 are at said second office.

54. In a telephone exchange system, a group of lines, other lines, a group of connecting circuits individual to said group of lines whereby they may be interconnected, 75 a second group of connecting circuits for connecting lines of said group to said other lines, means associated with the lines of said group for uniting said lines with connecting circuit of either of said groups, and means 80 whereby a line of said group is connected to a connecting circuit of said second group on the initiation of all calls, and whereby when the calling and called lines are both in the said group, the first seized connecting circuit 85 will be released and a connecting circuit individual to the said group of lines will be selected.

55. In a telephone exchange system, a group of lines, other lines, a plurality of 90 switches for interconnecting the lines of said group and a second plurality of switches for connecting the lines of said group to said other lines, controlling devices for governing the operation of said 95 switches, means operated upon the initiation of a call at one of the lines of said group whereby the controlling device thereof will be associated with one of said second plurality of switches, and apparatus which is 100 operated under the control of such controlling device when manipulated in accordance with the number of a subscriber in said group of lines to close a circuit whereby means will be actuated to release said selected switch and complete a talking circuit between the calling and called lines through 105 one of the first mentioned plurality of switches.

56. In a telephone system, a calling line, 110 a called line, a trunk line, means including a switching device for extending a connection from said calling line to said trunk line, fixed terminals accessible to said device, a non-numerical trunking switch individual to and terminating in said fixed terminals, movable terminals for said trunk line, means for operating said switching device to connect said movable and fixed terminals to control said trunking switch to 115 extend the connection to said called line.

57. In a telephone exchange system, a main office, a branch office, interoffice trunk lines from said branch to said main office, local trunk lines at said branch, automatic 120 switching mechanism at said main exchange and at said branch for effecting connection between subscribers, devices associated with the branch for controlling said switching mechanism, means whereby the first series 125 130

of selective impulses will effect the simultaneous actuation of switching mechanism at said main exchange and at said branch, and means operated under the control of a device when manipulated in accordance with the number of the called subscriber at said branch for releasing said main office switching mechanism and for establishing a talking connection through the switching mechanism at said branch.

58. In a telephone system, a main office, a branch office, a series of automatic switching mechanisms at said main office and at said branch respectively, whereby the line 15 of a calling subscriber may be extended to other subscribers at the main or at said branch, devices associated with said branch for controlling said switching mechanisms and means whereby the first series of impulses transmitted from one of said devices 20 will simultaneously effect the operation of switching mechanism at the main office and at the branch, and means operating when the called subscriber is at the branch for interrupting the controlling circuit to the 25 switching mechanism at the main exchange and for extending the line of the calling subscriber through branch switching mechanism to the line of the subscriber called.

59. In a telephone exchange system, a main office, a branch office, interoffice trunk lines between said branch and said main office, local trunk lines at said branch, means operated upon the initiation of a call at the 30 branch for associating the calling subscriber's line with an interoffice and a local trunk, automatic switching mechanism at said main office, and at said branch respectively, for establishing connection between subscribers, 35 devices associated with said branch for controlling said switches, and means operated under the control of a device when manipulated in accordance with the number of a called subscriber at the branch whereby the 40 first series of impulses will effect the simultaneous actuation of switching mechanism at said main exchange and at the branch, and the successive series will cut off the interoffice trunk and extend the connection through 45 the branch switching mechanism to the 50 called subscriber.

60. In a telephone exchange system, a main office, a branch office, interoffice trunk lines between said branch and said main office, local trunk lines at said branch, automatic switching mechanism at said main office, and at said branch for establishing connection between subscribers, said switching mechanism including a selector at said 55 branch, devices for controlling said switches, and means operated under the control of a device at the branch when manipulated in accordance with the number of a called subscriber at said branch, whereby said selector 60 and switching mechanism, at said main ex-

change will be simultaneously actuated by the first series of impulses, and whereby the successive series of impulses will cause the selector to alter an electrical circuit, and a relay in said circuit for effecting the release 70 of said main office mechanism.

61. In a telephone exchange system, a main office, a branch office, interoffice trunk lines between said branch and said main office, local trunk lines at said branch, automatic switching mechanism at said exchange and at said branch respectively for effecting connection between subscribers, devices at 75 said branch substations for controlling said switches, a cut-off relay, and means operated under the control of a device when manipulated in accordance with the number of a called subscriber at the branch, whereby switching mechanism at said main exchange and at the branch will be simultaneously actuated by the first series of impulses and the successive series will effect the energization 80 of said cut-off relay to interrupt the connection to the main office switching mechanism and extend the connection through the 85 branch switching mechanism to the called subscriber.

62. In a telephone exchange system, a main office, a branch office, interoffice trunks from said branch to said main office, local 95 trunks at said branch, automatic switching mechanism for establishing connection between subscribers, said switching mechanism including a selector at said branch, devices associated with said branch for controlling 100 said switches, means at said branch for associating the line of a calling subscriber therewith an interoffice trunk and a local trunk upon initiating a call whereby switching mechanism at the main office and at the 105 branch will be simultaneously actuated by the first series of impulses, a cut-off relay, said selector being operated under the control of a device when manipulated in accordance with the number of a called subscriber 110 at the branch to complete a circuit for said cut-off relay, whereby the interoffice trunk line will be interrupted and the connection will be completed through local switching mechanism.

63. In a telephone exchange system, a main office, a branch office, interoffice trunk lines from said branch to said main office, local trunks at said branch, automatic switching mechanism at said main exchange and at 120 said branch for establishing connection between subscribers, devices at said branch substations for controlling said switches, cut-off relays for interrupting said interoffice trunks, and means operated under the control of a device when actuated in accordance with the number of a called subscriber 125 at the branch whereby the simultaneous actuation of switching mechanism at said main exchange and at said branch will be effected 130

by the first series of impulses, and whereby the successive series will cause the energization of one of said cut-off relays and complete the connection through the branch 5 switching mechanism only when the called subscriber is at the branch.

64. In a telephone system, groups of subscribers' lines, automatic switches arranged in groups for interconnecting said lines, one 10 group of said switches being provided to extend a connection to lines of a certain group only, and other switches arranged to extend a calling line to subscribers' lines of other groups, devices for controlling said 15 switches, and means whereby the first series of impulses transmitted from one of said devices will simultaneously actuate a switch in said one group and a switch in one of the other groups, and means operating when the 20 calling and called lines are in the same group for completing the connection through that switch individual to said group and for interrupting the controlling circuit to the other switching mechanism.

65. In a telephone system, groups of subscribers' lines, automatic switches arranged in groups for inter-connecting said lines, one group of said switches being provided to extend the connection to lines of a certain 30 group and another group of said switches arranged to extend a calling line to other subscribers' lines, devices for controlling said switches, and means operating under the control of a device when actuated in accordance with the number of a called subscriber, whereby the first series of controlling 35 impulses will simultaneously actuate a switch in each of said groups, and whereby the succeeding series of impulses will extend the connection through only that one of said 40 simultaneously operated switches which has access to the group of the called subscriber.

66. In a telephone exchange, a group of subscribers' lines, other subscribers' lines, 45 automatic switches for interconnecting said lines, a group of switches for extending a connection to lines of said group only and other switches arranged to extend a connec-

tion to other subscribers' lines, devices for controlling said switches, and means operating under the control of a device when actuated in accordance with the number of a called subscriber whereby the first series of controlling impulses transmitted will simultaneously actuate a switch in said group and 50 one of said other switches, and whereby the succeeding series of impulses will extend the connection through one or the other of said simultaneously actuated switches according to whether the called subscriber is located 55 in the same group with the calling subscriber or is external thereto.

67. In a telephone system, a group of subscribers' lines, groups of switches for inter-connecting said lines, said groups of switches 60 being arranged to extend a connection to different groups of subscribers' lines, devices for controlling said switches, and means actuated upon the operation of one of said devices for first simultaneously actuating a 70 switch in each group and for subsequently releasing all but that one of said switches which has access to the line of the called subscriber.

68. In a telephone system, groups of subscribers' lines, groups of switches for inter-connecting said lines, the switches of said groups being arranged to extend a connection to different groups of subscribers' lines, devices for controlling said switches, and 75 means actuated when one of said devices is operated in accordance with the number of a called subscriber for first simultaneously actuating a switch in each group and for subsequently establishing the connection 80 through one of said switches to the line of the called subscriber and for effecting the return to normal of the other switches.

Signed by us at Chicago, Cook county, Illinois, this 5th day of August, 1913.

BERNARD D. WILLIS,
TALBOT G. MARTIN.
